(57) **CLAIM**

The ornamental design for a small cantilever mount for a flat panel display, as shown and described.

DESCRIPTION

FIG. 1 is a top, right isometric view of a small cantilever mount with a tilt mechanism for a flat panel display showing our design.

FIG. 2 is a front elevational view thereof.

FIG. 3 is a rear elevational view thereof.

FIG. 4 is a right-side elevational view thereof.

FIG. 5 is a left-side elevational view thereof; and,

FIG. 6 is a top plan view thereof; the bottom plan view is a mirror image of FIG. 6.
